UNITED STATES PATENT OFFICE.

WILLIAM J. LOGAN, OF CLEVELAND, OHIO.

POWDERING-MACHINE FOR PLATES TO BE ETCHED.

1,290,603.

Specification of Letters Patent.

Patented Jan. 7, 1919.

Application filed December 28, 1916. Serial No. 139,306.

To all whom it may concern:

Be it known that I, WILLIAM J. LOGAN, a citizen of the United States, residing at Cleveland, in the county of Cuyahoga and State of Ohio, have invented certain new and useful Improvements in Powdering-Machines for Plates to be Etched, of which the following is a specification.

This invention relates to a machine for powdering printing plates preparatory to being etched, and has for its principal object to provide a machine capable of automatically carrying out the necessary successive operations for the accomplishment 15 of this purpose.

The plate to be powdered is laid upon the roller table of the machine, and it is carried through a chamber where the etching powder falls upon it. The powder covered plate 20 passes under a stationary brush for removing the surplus powder and under transversely moving brushes for banking the remaining powder on the plate against the lines of the design, and then over gas burners for baking the powder to the plate. After the baking process, the plate is cooled 25 by air blast, and then travels back through the powdering chamber for another covering of powder. At this point, the plate is given a one-quarter turn, and as it passes 30 under the before mentioned brushes, it is dusted transversely to the first brushing. The powder is then baked to the plate as before, and the plate again cooled. The 35 plate then travels back through the powdering chamber and said operations are repeated until the plate has been powdered and brushed four times, and the powder baked to the plate and the plate cooled each 40 time, which prepares it for etching.

By the use of this machine, plates are powdered uniformly without the employment of skilled labor. It simply being necessary to place the plates in the machine 45 and the various successive steps will be carried out automatically.

In order that the invention may be clearly understood, the same will be hereinafter fully described in connection with the accompanying drawings, which are intended to simply illustrate the invention without limiting it to the particular form shown, and the novel features thereof will be distinctly pointed out in the appended claims.

In the drawings like characters of reference indicate corresponding parts. 55

Figure 1 is a front elevation of a machine constructed in accordance with my invention. 60

Fig. 2 is a plan view of the same, Fig. 3 is a rear elevation of the machine, Fig. 4 is a cross sectional view, taken on line 4—4 of Fig. 3,

Fig. 5 is a similar view taken on line 5—4 of Fig. 3, 65

Fig. 6 is a view of a rear portion of the machine, the control carriage being at the commencement of its advance movement,

Fig. 20 is an elevation of the powder brushing mechanism,

Fig. 21 illustrates the driven sprocket wheel shaft of same, and

Fig. 22 is a perspective view of a brush 100 attached to its support.

Frame.—The frame of the machine consists of a pair of top side bars 1 and end bar 2, which are supported by end legs 3 and intermediate legs 4 and 5. Other similar side bars 6 and cross bars 7 connecting the same serve to give rigidity to the frame. 105

Roller table. (Figs. 1—4.)—To the top side bars 1 are fixed pairs of transversely alining

bearings 8, in which are mounted shafts 9 carrying disks 10 to form a roller table, and a pair of similar shafts 11 supporting elongated rollers 12, which carry endless belts 13 having bars 14 attached thereto to form a cooling platform. Said shafts extend beyond one side of the frame, are driven by similar bevel gears 15, which are driven by similar bevel gears 16 carried by a longitudinal shaft 17. This last named shaft is supported by bearings 18 fixed to the frame of the machine, and at one end thereof is a gear wheel 19, which is in mesh with a pinion 20 secured to a driving shaft 21. This driving shaft is mounted in bearings 22 carried on the legs 3 and 5, and is adapted to be driven in either direction by means of a pair of the usual opposite bevel wheels 23 and 24, which are loosely mounted on said shaft and driven by a bevel wheel 25. A clutch 26 being feather keyed to the shaft for causing either of said bevel wheels to rotate the shaft. The bevel wheel 25 is fixed to one end of an inclined shaft 27, which is supported in suitable bearings attached to the frame of the machine, and at the other end of this shaft is a bevel pinion 28, which meshes with a similar bevel pinion 29 secured to a longitudinal shaft 30 supported by bearing fixed to cross pieces 31 of the frame. The shaft 30 is driven from a shaft 32, which is supported in bearings also carried by said cross pieces of the frame, and the latter shaft is driven by an electric motor 33, which transmits power through a chain 34 to a sprocket wheel 35 on the shaft. Said shafts are operatively connected together by means of a pinion 36 meshing with a gear 37. A shelf 38 attached to the frame is provided for supporting the motor.

Roller table reversing mechanism, (Figs. 3, 6 and 7.)—The before mentioned clutch 26 is slidably moved upon the shaft 21, to engage either of the bevel wheels 23 or 24 for causing rotation of said shaft in either direction, by means of the mechanism now to be described. Said clutch is engaged by a depending arm 39 fixed to a shift rod 40, which is slidably mounted in guide brackets 41 on the legs 4 and 5. Fixed on said rod are a pair of suitably spaced collars 42 and 43, and around the rod are coiled springs 44 and 45, which are adapted to abut said collars. A pair of locking levers 46 and 47 are pivoted to a plate bracket 48 attached to a top side bar of the frame, and these arms carry blocks 49 and 50 for engaging the upper outer edges of said collars for holding the clutch 26 in engagement with either of the bevel wheels 23 or 24. The shift rod 40 is forced longitudinally in either direction by a control carriage 51. Projecting from the control carriage is an arm 52 having a bifurcated end 53 for straddling the shift rod and for engaging the free ends of the

coiled springs 44 and 45 for compressing the same. The arm 52 carries horizontal arms 54 and 55 having rollers 56 at their ends, for engaging cams 57 and 58 depending from the locking levers 46 and 47 respectively to force the same out of locking position. When said locking levers release the shift rod 40, it is forced longitudinally by the action of the compressed springs 44 and 45.

Control carriage, (Figs. 3, 6 and 7.)—The control carriage 51 is supported upon the threaded portion of a worm shaft 59, which is rotatably mounted in bearings 60 and 61 fixed to the legs 4 and 5 respectively. Said worm shaft is driven in either direction from the shaft 21, by means of the pinion 62 and gear 63, which are fixed to said shafts. This imparts reciprocating motion to the control carriage.

Turning rack, (Figs. 1-4, 6, 7, and 13-16.)—At the opposite end of the roller table from the cooling platform is arranged a turning rack, which consists of a central hub 64 fixed to an upright rod 65 and carrying bars or slats 66 forming a rectangular shaped top adapted to straddle the disks 10 of the roller table. The purpose of this turning rack is to rotate the plate being prepared for etching a quarter turn each time it is powdered. Said turning rack top is normally below the upper edges of the disks 10, and when the plate is carried to a position over the same, it rises up clear of the disks, thereby lifting the plate, and gives it a quarter turn. This is done by the action of the control carriage 51 through the following mechanism. On the upright rod 65 of the turning rack is a fixed flange 67, which is engaged by the forked end 68 of a lever 69 fulcrumed at 70 to a cross piece 71 of the frame. The other end 72 of this lever is pivotally connected at 73 to a strap 74 which depends from and is pivoted at 75 to a sleeve 76 loosely mounted upon the worm shaft 59. The lower end of the upright rod 65 is slidably mounted in a guide bracket 77 fixed to a pair of cross pieces 78 of the frame, and is feather keyed at 79 to a ratchet wheel 80 resting upon said guide bracket. A flanged bushing 81 is rotatably mounted upon the upright rod above said ratchet wheel, and a spring pressed pawl 82 pivoted thereto is adapted to engage the teeth of the ratchet wheel for causing rotation of the turning rack. For keeping the flanged bushing in engagement with said guide bracket, a coiled spring 83 is interposed between the forked end 68 of the lever 69 and the bushing. To said bushing at 84 is connected one end of a belt 85, which partially winds around the same. The other end of said belt is attached to a wire rod 86, and the free end of this wire rod is pivotally connected to an arm of a bell crank 87,

which is pivoted to a base 88, fixed to a lower side bar of the frame. The other arm of said bell crank is pivotally connected to a sliding joint member 89, which is connected to the pivot point 73 of the lever and strap. As the control carriage 51 advances, it moves the sleeve 76 longitudinally, thereby forcing the end 72 of the lever 69 downwardly and lifting the turning rack clear 10 of the disks 10 of the roller table. As soon as the turning rack is lifted clear of the disks, the sliding joint member 89 has closed up and the bell crank 87 is actuated. The bell crank pulls upon the wire rod 86, which 15 by unwinding the belt 85, rotates the flanged bushing 81 and together with the same the turning rack is rotated a quarter of a revolution. Upon the return movement of the control carriage, the turning rack will drop by 20 gravity, and one of four guide pins 90 extending horizontally from the upright rod 65, will enter a slot 91 in a guide plate 92 fixed to the guide bracket 77, which insures the plate being prepared for etching being 25 left squarely upon the roller table.

Powdering chamber, (Figs. 1-3.)—Arranged near the turning rack, is a chamber 93, which incloses mechanism for sprinkling powder over the surface of the plate being 30 prepared for etching, and also mechanism for brushing said powdered surface. The chamber preferably consists of a lower box like portion 94, having an inclined bottom 95, which slopes to a transversely extending 35 trough 96, and a removable cover 97. Said lower portion of the chamber is supported from the top side base of the frame, and the front and rear sides thereof are provided with elongated openings 98 and 99 respectively for permitting the plate to pass 40 through the chamber.

Powder sprinkling mechanism, (Figs. 17-19.)—A tapering hopper 100 for containing the powder is supported above the 45 trough 96 by upright brackets 101 fixed to the frame and extending into the chamber, and its bottom is provided with a longitudinal outlet 102, which is closed by a corrugated roller 103 having its shaft 104 pivoted 50 in said upright brackets. A circular brush 105 is arranged in contact with the corrugated roller for keeping the same clean, and its spindle 106 is rotatably mounted in lateral extensions 107 of the upright brackets 55 101. Guide plates 108 and 109 are fixed to the hopper for directing the powder as it falls therefrom. Said corrugated roller is driven from one of the roller table shafts 9, and is adapted to be rotated for sprinkling 60 the powder, only when the plate being prepared for etching is being carried toward the turning rack end of the roller table. This is carried out by loosely mounting a sprocket wheel 110 on the roller shaft 104, 65 which is driven by a sprocket chain 111 pass-

ing over a sprocket wheel 112 fixed to a roller table shaft 9. A spring pawl 113, carried by the sprocket wheel 110, is adapted to engage the ratchet teeth 114 on the side of a gear 115, which is fixed to the roller shaft 70 104, and drive said corrugated roller when the roller table shaft 9 is rotating in one direction but not in the other. The circular brush 105 is rotated from the roller 103 by the gear 115 meshing with a gear 116 fixed 75 to its spindle 106. Another brush 117 is arranged adjacent the powder hopper 100 for removing the surplus powder from the plate being prepared for etching as it travels under the same. This brush is adapted to be 80 raised clear of the plate when the plate is traveling under the brush on its return. Supporting the brush 117 are a pair of arms 118, which are slidably mounted in slotted guides 119 of the bracket extensions 107, and 85 depending from said arms are legs 120 having inturned ends 121 for co-operating with cams 122 fixed to the roller table shaft 9. Said cams are cylindrical and at one side are provided with spiral grooves 123 leading 90 from the outer edges thereof to their centers for receiving said inturned ends 121. Suitable flat springs 124 are arranged in the cams across the inner ends of the spiral grooves. When the cams 122 rotate clockwise, the inturned ends 121 rest upon the shaft 9 and the brush 117 will be held in its down position. The moment the cams rotate in the opposite direction, said inturned ends cannot pass the 95 free inner ends of the flat springs and will 100 be thrown by the action of the spiral grooves to the outer edges of the cams, thereby raising the brush and holding it clear of the plate. When the cams again change their 105 direction of rotation, the inturned ends will enter the spiral grooves and the brush will be returned to its down position.

As the powder falls from the hopper 100 and also as it is brushed from the plate being prepared for etching, it runs into the 110 trough 96 of the chamber 93. From said trough, the powder is carried back to the hopper by a bucket conveyer now to be described. A pair of axles 125 and 126 are rotatably mounted in the sides of the trough, 115 and fixed to these axles are pairs of sprocket wheels indicated by 127. Corresponding pairs of similar sprocket wheels 128 are rotatably mounted on stub axles 129 extending inwardly from pairs of posts 130, which project above and are fastened to the ends of the powder hopper. A pair of endless sprocket chains 131 pass around said 120 sprocket wheels, and these chains are connected together at intervals by pins 132, to 125 which are pivoted a rear edge of buckets 133. The sprocket wheels 127 are so arranged that said buckets will scrape along the bottom of the trough 96, and a guide rail 134 supported 130 from the chamber by brackets 135, is pro-

vided for preventing the buckets' tipping forwardly as they travel above the hopper and downwardly. The sprocket chains 131 are adapted to travel in but one direction, 5 and only when the corrugated roller 103 is rotating for sprinkling the powder.

The axle 125 is driven from the shaft 21, by means of a sprocket chain 136, which passes over a sprocket wheel 137 fixed to said 10 shaft. This chain drives a sprocket wheel 138 loosely mounted on the axle 125, and a spring pawl 139, carried by this sprocket wheel, is adapted to engage the ratchet teeth on the side of a wheel 140 fixed to the 15 axle, and thereby rotate the axle only when the shaft 21 is rotating in one direction.

Brushing mechanism, (Figs. 20-22.)—After being powdered, the plate, on its return through the chamber 93, passes beneath 20 a plurality of transversely moving brushes 141, carried by an endless sprocket chain 142, which travels over a pair of sprocket wheels 143 fixed to spindles 144 and 145. These spindles are rotatably mounted in standards 25 146 projecting upwardly from the frame. Each of the brushes 141 is adjustably attached, as at 147, to a plate 148, which is cut out at 149 for straddling the sprocket chain, and a pair of right angle ears 150 30 projecting therefrom are pivotally connected to a pin 151 of the chain. It is important that the brushes move evenly over the powdered surface of the plate, and this is accomplished by providing suitable tracks 152, 35 which are fixed to the standards 146 for supporting roller wheels 153 on the pins 151 of the sprocket chain. It will be noted that the chain sags under its own weight, and this tends to keep the roller wheels upon 40 the tracks. The brushes 141 always travel in the same direction across the powdered plate and incline rearwardly with relation to the movement of the chain. The edges 154 of the cut out portions of the plates 148, 45 by engaging the sprocket chain, limit the inclination of the brushes. Motion is imparted to the spindle 144 from the shaft 21, by a sprocket chain 155, which passes around a sprocket wheel 156 fast on said shaft, and 50 over a sprocket wheel 157, loosely mounted on said spindle. The sprocket wheel 157 carries a spring pawl 158, which is adapted to engage the ratchet teeth of a wheel 159 secured to the spindle for rotating the same.

Powder baking burners and means for operating same, (Figs. 1-4 and 8, 9, 12.)—The powder is baked to the plate after leaving the chamber 93 as it travels over a plurality of gas burners 160 in the form of tubes arranged 60 between the rows of disks 10. These tubes are bent under at 161 and terminate in a common header 162, which is connected by a vertical pipe 163 to an elongated reservoir 164 supported by the cross pieces 31 of 65 the frame. Gas is supplied to said reservoir

from any suitable source. An ordinary shut off valve 165 having a plunger 166, which is adapted to be forced inwardly for opening the valve, is arranged in the vertical pipe 163. This valve is automatically opened by 70 the carriage 51 to admit gas to the burners, which become ignited from suitable pilot lights 167 connected to the reservoir 164, and locked in open position until the plate has passed over said burners. A lever 168, pivoted at 169 to a cross piece 170 of the frame, is adapted to force the plunger of the valve 165 inwardly, and to the upturned bifurcated free end, 171, of this lever is pivotally attached a push rod 172 having its other 75 end slidably supported in a bearing box 173 fastened to the leg 4 of the frame. Said push rod is forced longitudinally to open said valve by means of an arm 174, which is rotatably connected to the end of the carriage 51 by a flange 175, and is adapted to engage a lug 176 on the rod. A suitable spring 177 tends to press the arm 174 toward the push rod. The valve is locked open by means of a bar 178, having one end 80 pivoted at 179 to the leg 4 of the frame, and carrying a block 180, which is adapted to engage a collar 181 fixed to the push rod 172. After the arm 174 has moved said push rod to its locked position, it is disengaged from 85 the lug 176 by sliding over a stationary cam plate 182 fixed to the frame, and at the proper time will raise the locking bar 178 out of engagement with the collar 181, thereby allowing the shut off valve 165 to close. 90 The inclined free end 183 of the locking bar permits the same to be raised and fall at the proper time.

Cooling platform and mechanism for stopping and reversing same, (Figs. 1-3 and 5 105 and 10-12.)—When the powder has been baked to the plate, it is carried onto the before mentioned cooling platform, which is automatically stopped, while the plate is cooled by air furnished by a blower 184 and 110 delivered through a pipe 185 having a nozzle 186 for directing the same against the plate, and then the cooling table is caused to travel in the reverse direction. As already described, the control carriage 51 actuates the 115 shift rod 40 for moving the clutch 26 and thereby causing the roller table and the cooling table to carry the plate in either direction. When the control carriage forces the shift rod to the left, the clutch 26 engages 120 the bevel wheel 24, and a pawl 187, which is pivoted at 188 to the frame with its free end resting upon the push rod, falls into a notch 189 cut therein. Upon the return of the control carriage, it forces the shift 125 rod to the right until the shoulder of said notch strikes the pawl 187. This leaves the clutch 26 in neutral position between the bevel wheels 23 and 24, and the roller table and cooling platform remain stationary. At 130

the same time that the control carriage 51 is advancing and returning, a releasing carriage 190 supported on the threaded portion 191 of a shaft 192, which is rotatably mounted in the bearing 60 and a bearing 193 fixed to an upright 194 of the frame, is also moving in the first direction for releasing the shift rod 40. The threaded shaft 192 is driven from the shaft 30 by means of a 10 sprocket chain 195, which passes over sprocket wheels 196 and 197 fixed respectively to said shafts. A toothed bar 198 is slidably mounted in said releasing carriage, and when in its down position its teeth 199 15 are adapted to engage the threads 191 of said shaft. The upper end of the toothed bar 198 is provided with a hollow space 200, in which is rotatably mounted a roller wheel 201 for running upon a guide bar 202, which 20 is pivotally connected to the leg 4 and upright 194 by a pair of links 203 and 204. The guide bar 202 is held in its down position by means of a locking pawl 205, which is pivoted at 206 to a piece 207 extending 25 from the frame. Said locking pawl is provided with a lateral nose 208, which is adapted to engage the edge of a recess 209 in the upper edge of the guide bar 202. A spring 210 tends to keep the pawl 205 in 30 locking position. The releasing carriage 190 is caused to move in one direction by the rotation of the threaded shaft 192, and at the proper time, an arm 211 carried by the carriage strikes the pawl 187 and forces it 35 out of engagement with the shoulder of the notch 189 of the shift rod 40. Upon being released, the shift rod is forced to the right by the compressed spring 44, and the clutch 26 brought into engagement with the bevel 40 clutch 23. Both the roller table and the cooling platform now begin to travel in the opposite direction from that before they came to a standstill. At the moment the arm 211 strikes the pawl 187, a finger 212 projecting 45 from the releasing carriage 190 engages the curved edge 213 of the locking pawl 205, and forces it laterally out of engagement with the guide bar 202, which is thrown up by the tension of a coiled spring 214 connected to 50 the link 204 and carriage 190. This raises the toothed bar 198 out of engagement with the shaft 192, and the carriage is drawn back to a stop 215 on the shaft by the action of the coiled spring 214. The guide bar 202 is 55 forced to its down position by the control carriage 51. Upon its return movement, the control carriage actuates a push bar 216 pivotally connected at 217 to the link 203 and having its free end slidably supported in 60 the bifurcated end of an arm 218 projecting upwardly from the carriage. In order that the guide bar will not be forced down too suddenly, a coiled spring 219 is arranged on the push bar with one end abutting a collar 65 220 thereon, and the arm 218 is adapted to

act against the other end of the spring. Said collar is adjustably fixed to the push bar by a screw 221, so that it may be set to a suitable position for obtaining smooth action of the guide bar.

Mechanism for stopping the machine, (Figs. 3 and 5-7.)—As it is necessary to powder the plate four times in preparing it for etching, it must travel back and forth upon the roller table that number of times. When

70 the plate has been carried back and forth four times the roller table is stopped by mechanism operated from the control carriage 51, which throws a switch for stopping the motor 33. This mechanism consists of a

75 bar 222, which is slidably mounted in the leg 4 and upright 194, and provided with two sets of ratchet teeth 223 and 224. There

are four teeth to each set. A coiled spring 225 having one end fastened to said bar and 80 its other end to the leg 4, is adapted to force the bar to the left, and in so doing, a pin

226 carried thereby and engaging the lever 227 of a switch 228, closes the switch and 85 starts the motor 33. A spring 229 tends to draw the lever 227 toward the leg 4 and close 90 the switch. Said switch is fixed to a lower side bar of the frame, and is connected to a suitable electric circuit and to the motor in the usual manner. The moment the

95 switch is closed, the notched end 230 of a weighted lever member 231 pivoted at 232 to the leg 4, engages a nib piece 233, which is fixed to the switch lever 227, and locks 100 the lever against movement. Before the bar 222 can slide for the purpose of closing the switch, it is necessary to release it by raising a locking dog 234, which is pivoted to the leg 4, and is adapted to engage the ratchet teeth 223, and also to raise a push 105 pawl 235, which is pivotally connected to a depending lever 236 having its upper end pivoted to a top side bar of the frame. This is done by shifting a handle 237 fixed to a rod 238, which is rotatably supported by the legs 3 and 4 of the frame, and from said rod project arms 239, to which said latch and pawl are connected by chains indicated by 240. From the depending lever 236 projects a pin 241, which is adapted to be engaged by the arm 174 of the control carriage 51 for pushing the lever to the right.

110 A guide pin 242, projecting from the leg 4, passes freely through the lever at 243, and on this guide pin between the leg and lever is a coiled spring 244 for forcing the lever to the left. A nut 245 on the guide pin limits the movement of the lever. Each time

115 the control carriage 51 advances to the left, the coiled spring 244 forces the lever 236 in that direction, and when it returns, its arm 174 engages the pin 241 and forces the lever to the right. This causes the push

120 pawl 235 to move the bar one tooth forward, and the locking dog 234 will prevent it mov-

125 130

ing backward. Upon moving the bar 222 the distance of four teeth, a trolley wheel 246 carried by the bar will press the curved end 247 of the lever 231 downwardly and thus disengage its other end from the nib piece 233. The switch lever 227 will then be thrown open by the action of the spring 229, and the machine stopped.

The operation follows: The plate to be prepared for etching is laid squarely upon the cooling platform 14. Before starting the machine, the control carriage 51 and all of the other parts are in the positions best shown as a whole in Fig. 3. By shifting the handle 237, the locking dog 234 and push pawl 235 are disengaged from the ratchet teeth 223 and 224 respectively of the bar 222, and the coiled spring 225 forces said bar to the left (Figs. 6 and 7). The pin 226 carried by this bar being forced against the lever 227, closes the switch 228, thereby starting the electric motor 33. Power is transmitted from the motor to the shaft 32, Fig. 5, thence to the shaft 30, and through the inclined shaft 27 to the bevel wheels 23 and 24. As the clutch 26 engages the bevel wheel 23, the shaft 21 is rotated clockwise, and motion is transmitted by the pinion 20 on this shaft to the gear wheel 19, which causes rotation of the longitudinal shaft 17 (Fig. 3). The bevel gears 16 on this shaft drive the bevel gears 15, and thus rotate all of the shafts 9 carrying the disks 10 and also the shafts 11 of the cooling table, in the proper direction for causing the aforesaid plate being prepared for etching to travel toward the other or turning rack end of the roller table.

When the shafts 9 are rotating as just stated, motion is transmitted through the sprocket chain 111 (Fig. 18) and by the action of the spring pawl 113, to the corrugated roller 103 for causing the powder to fall from the hopper 100. The circular brush 105 is rotated from the action of the corrugated roller by means of the meshing gears 115 and 116, and the brush 117 is forced downwardly and held in its down position by the spiral groove cams 122. As the plate travels under the hopper, the powder falls thereon, and as it passed under the brush 117, the surplus powder is removed from the plate.

While the plate is being carried toward the turning rack end of the roller table, the shaft 21 is driving the worm shaft 59, through the agency of the pinion 62 and the gear 63, so that the control carriage 51 is caused to advance by the rotation of said worm shaft. The arm 52 of the control carriage compresses the coiled spring 45, and when the locking lever 47 is disengaged from the collar 48 of the shift rod 40 by the roller 56 striking the cams 58, said compressed coiled spring forces the shift rod to

the left. The clutch 26 being forced into engagement with the bevel wheel 24 causes the shaft 21 to revolve in the opposite direction and thereby reverse the travel of the roller table. The block 49 of the locking lever 46, 70 by falling back of the collar 42, holds the shift rod against movement.

Before the travel of the roller table is reversed, and as soon as the plate is directly above the turning rack 66, the control carriage 51 (Figs. 6 and 7), in its advancing movement, by forcing the sleeve 76 along the worm shaft, actuates the fulcrumed lever 69 and thereby raises the turning rack clear of the disks 10 and with it the plate. As the control carriage continues to advance, the sliding joint member 89 is closed up and the bell crank 87 actuated. This pulls upon the wire rod 86, and the unwinding of the belt 85 rotates the flanged bushing 81, thus causing the pawl 82 to rotate the turning rack a quarter turn. Upon the reversing of the rotation of the shaft 21, the rotation of the worm shaft 59 is reversed and the control carriage forced to return to its original position. As the control carriage recedes from the sleeve 76, the turning rack falls by gravity and leaves the plate resting upon the disks 10 of the roller table, which now carry it back toward the cooling platform 14. 95 The moment the shaft 21 changed its direction of rotation, the brushes 141, (Fig. 20), which have been at rest, begin to move due to the action of the spring pawl 158 (Fig. 21) driving the spindle 144, and thereby moving the sprocket chain 142 carrying the brushes. As the powder covered plate passes under these transversely moving brushes, it is brushed in one direction.

As soon as the plate has been brushed, the arm 174 (Figs. 8, 9 and 12) of the control carriage 51 engages the lug 176, and forces the push rod 172 to the right. This opens the valve 165, and gas is admitted to the burners 160, which become ignited from the pilot lights 167. When the push rod 172 is actuated, the block 180 of the locking bar 178 engages the collar 181, and the valve 165 is held open. As the powder covered plate passes over the ignited gas burners, the powder is baked thereto. Just as soon as the plate is carried past the last burner, the arm 174 of the control carriage, having been thrown up by sliding on the cam plate 182, is disengaged from the lug 176, and at the proper time forces the locking bar 178 out of engagement with the collar 181 of the push rod. Upon releasing the push rod the valve 165 automatically closes and gas is shut off from the burners.

After the powder has been baked to the plate, it passes onto the moving platform 14 (Fig. 3) under the air blast from the nozzle 186, and upon reaching a central position thereon, the platform stops for allowing the 130

plate to be cooled by said air blast. When the shift rod 40 was forced longitudinally by the control carriage to move the clutch 26 into engagement with the bevel wheel 24, the 5 pawl 187 (Figs. 10, 11 and 12) dropped into the notch 189 of the shift rod, but the shoulder of the notch was in advance of the pawl. As the control carriage returns to its original position, its arm 53 compresses the coiled 10 spring 44, the shift rod 40 being held by the locking lever 46. At the same time that the plate reaches the center of the platform, the roller 56, carried by the arm 54 of the control carriage, strikes the cam 57 and forces 15 the locking lever 46 to release the shift rod. Upon being released, the shift rod is forced longitudinally, by the action of the compressed spring 44, until the shoulder of its notch 189 strikes the pawl 187. This brings 20 the clutch 26 to its central or neutral position between the bevel wheels 23 and 24, and the shaft 21 not being rotated, the roller table and also the platform come to a standstill. When the plate has been subjected to 25 the air blast a sufficient length of time for being cooled, the pawl 187 is lifted out of engagement with the shoulder of the notch 189 of the shift rod 40, by the arm 211 of the releasing carriage 190, and the shift rod 30 is forced longitudinally by the compressed coiled spring 44 to bring the clutch 26 into engagement with the bevel wheel 23. This causes the shaft 21 to be driven in the direction first mentioned, and the cooling platform and also the roller table to travel in 35 the opposite direction from that before they came to a standstill. The plate therefore is carried again to the other or turning rack end of the roller table. Said releasing carriage 190 is advanced by the rotation of the threaded shaft 192, which is driven continuously in one direction from the shaft 30 through the medium of the sprocket chain 195 (Fig. 5). The guide bar 202 being in its 40 down position, allows the teeth 199 of the toothed bar 198 to engage the threads of the shaft 192 and the carriage is thus advanced. At the proper time, said guide bar, which has been held in its down position by the locking pawl 205, is released by the finger 212 striking the curved edge 213 of the locking pawl and forcing it out of engagement with the guide bar. As soon as released, the guide bar is thrown up by the action of the 45 coiled spring 214, the toothed bar 198 is thereby lifted out of engagement with the threaded shaft 192, and said coiled spring now serves to draw the releasing carriage back to the stop 215. Said guide bar is 50 gently forced to its down or original position by the arm 218 of the control carriage 51, upon its return movement, pressing against the coiled spring 219 on the push bar 216. Due to the action of the spring 210, the 55 nose 208 of the locking pawl 205 enters the recess 209, and the guide bar is held in its down position as before.

Upon starting the machine by shifting the handle 237, and thus allowing the bar 222 (Figs. 6 and 7) to be forced longitudinally 70 by the coiled spring 225, the locking dog 234 will rest against the shoulder of the last ratchet tooth 223 and the push pawl 235 will rest upon the next to the last ratchet tooth 224. As the control carriage 51 advances, its arm 75 174, which has been engaging the pin 241 carried by the depending lever 236, permits the lever to swing in the same direction due to the action of the coiled spring 244 on the guide pin 242. This allows the push pawl 80 235 to fall back of the shoulder of the last ratchet tooth 224. When the control carriage returns, its arm 174, by engaging said pin 241, will actuate the lever and cause the push pawl to force the bar 222 one tooth to 85 the right, and the locking dog 234 will drop back of the second ratchet tooth 223 thus holding the bar against backward movement. Each time the control carriage 51 advances and returns, the bar 222 is moved one tooth, 90 and when it has moved the distance of four teeth, the trolley wheel 246, by forcing the curved end 247 of the lever member 231 downwardly, disengages its notched end 230 from the nib piece 233, and the switch 228 is 95 opened by the action of the coiled spring 229. The machine is thus automatically stopped, when the plate is upon the cooling platform. When the plate being prepared for etching has been carried four times back 100 and forth upon the roller table, each time going through the operations described, it has been powdered four times, brushed in four different directions, the powder baked to the plate, and the plate cooled after each 105 brushing.

Having fully described my invention, what I claim is:

1. In a plate powdering machine, means for carrying a plate, means for holding powder above the travel of the plate, means for causing the powder to fall upon the plate as it travels along, and means for brushing the powder upon the plate in one direction and transversely to the travel of the plate. 110
2. In a plate powdering machine, means for carrying a plate, means for holding powder above the travel of the plate, means for causing the powder to fall upon the plate as it travels along, transversely traveling brushes for brushing the powder in one direction over the surface of the plate, and means for baking the powder to the plate. 120
3. In a plate powdering machine, means for carrying a plate, means for holding powder above the travel of the plate, means for causing the powder to fall upon the plate as it travels along, transversely traveling brushes for brushing the powder in one direction over the surface of the plate, means 125

65 nose 208 of the locking pawl 205 enters the

for baking the powder to the plate, and means for cooling the plate.

4. In a plate powdering machine, means for carrying a plate, means for holding powder above the travel of the plate, means for causing the powder to fall upon the plate as it travels along, means for brushing the powder in one direction over the surface of the plate, means for baking the powder to the plate, means for cooling the plate, and means for automatically stopping the machine.

5. In a plate powdering machine, means for carrying a plate, means for holding powder above the travel of the plate, means for causing the powder to fall upon the plate as it travels along, means for brushing the powder over the surface of the plate, means for baking the powder to the plate, means for cooling the plate, means for automatically stopping the means for carrying a plate, and means for automatically starting the means for carrying a plate after being stopped.

25 6. In a plate powdering machine, means for carrying a plate, means for holding powder above the travel of the plate, means for causing the powder to fall upon the plate as it travels along, means for brushing the powder over the surface of the plate, means for baking the powder to the plate, means for cooling the plate, means for automatically stopping the means for carrying a plate during the cooling of the plate, means for starting the means for carrying a plate after being stopped, and means for reversing the travel of the means for carrying the plate after the stopping of the same.

7. In a plate powdering machine, means for carrying a plate, means for holding powder above the travel of the plate, means for causing the powder to fall upon the plate as it travels along, means for brushing the powder over the surface of the plate, means for baking the powder to the plate, means for cooling the plate, means for automatically stopping the means for carrying a plate, means for automatically starting the means for carrying a plate after being stopped, means for automatically reversing the travel of the means for carrying the plate after the stopping of the same, and means for turning the plate a part of a revolution.

55 8. In a plate powdering machine, the combination of a roller table for carrying a plate, means for driving the roller table, a hopper for holding powder arranged above the roller table, means for causing the powder to fall upon the plate, a vertically movable brush adapted to remove the surplus powder from the plate, and means for automatically moving said brush.

9. In a plate powdering machine, the

combination of a roller table for carrying a plate, means for driving the roller table, a hopper for holding powder arranged above the roller table, means for causing the powder to fall upon the plate, a vertically movable brush adapted to remove the surplus powder from the plate, means actuated from the roller table for moving said brush, and transversely moving brushes for brushing the powder over the surface of the plate.

10. In a plate powdering machine, the combination of a roller table for carrying a plate, means for driving the roller table, a hopper for holding powder arranged above the roller table, means for causing the powder to fall upon the plate, a vertically movable brush adapted to remove the surplus powder from the plate, means for moving said brush, transversely moving brushes for brushing the powder over the surface of the plate, and means for baking the powder to the plate.

11. In a plate powdering machine, the combination of a roller table for carrying a plate, means for driving the roller table, a hopper for holding powder arranged above the roller table, means for causing the powder to fall upon the plate, a vertically movable brush adapted to remove the surplus powder from the plate, means for moving said brush, transversely moving brushes for brushing the powder over the surface of the plate, means for baking the powder to the plate, and means for cooling the plate.

12. In a plate powdering machine, the combination of a roller table for carrying a plate, means for driving the roller table, a hopper for holding powder arranged above the roller table, means for causing the powder to fall upon the plate, a vertically movable brush adapted to remove the surplus powder from the plate, means for moving said brush, transversely moving brushes for brushing the powder over the surface of the plate, burners for baking the powder to the plate, and an air blast for cooling the plate.

13. In a plate powdering machine, the combination of a roller table for carrying a plate, means for driving the roller table, a hopper for holding powder arranged above the roller table, means for causing the powder to fall upon the plate, a vertically movable brush adapted to remove the surplus powder from the plate, means for moving said brush, transversely moving brushes for brushing the powder over the surface of the plate, means for reversing the travel of the roller table, and means for turning the plate so that said transversely moving brushes will brush it in different directions.

14. In a plate powdering machine, the combination of a roller table for carrying a plate, means for driving the roller table,

5 a hopper for holding powder arranged above the roller table, means for causing the powder to fall upon the plate, a vertically movable brush adapted to remove the surplus powder from the plate, means for moving said brush, transversely moving brushes for brushing the powder over the surface of the plate, means for reversing the travel of the roller table, means for turning the plate so
10 that said transversely moving brushes will brush it in different directions, means for baking the powder to the plate after each transverse brushing, and means for cooling the plate after each baking of the powder
15 thereto.

15. In a plate powdering machine, the combination of a roller table for carrying a plate, means for driving the roller table, a powder hopper arranged above the roller table, transversely movable brushes for brushing the plate, means for reversing the travel of the roller table, means for causing powder to fall from said hopper when the plate is being carried in one direction, and
20 means for operating said brushes when the plate is being carried in one direction.

16. In a plate powdering machine, the combination of a roller table for carrying a plate, means for driving the roller table, a powder hopper arranged above the roller table, transversely movable brushes for brushing the plate, means for reversing the travel of the roller table, means for causing powder to fall from said hopper when the plate is being carried in one direction, means for operating said brushes when the plate is being carried in one direction, gas burners for baking the powder to the plate after being brushed, means for operating the gas
30 burners, means for shutting off the gas burners, and means for cooling the plate after the powder has been baked thereto.

17. In a plate powdering machine, the combination of a roller table for carrying a plate, means for driving the roller table, a powder hopper arranged above the roller table, transversely movable brushes for brushing the plate, means for causing powder to fall from said hopper when the plate
35 is first passing thereunder, means for turning the plate a part of a revolution after passing under the hopper, means for reversing the travel of the roller table, and means for operating said brushes after the reversing of the travel of the roller table.

18. In a plate powdering machine, the combination of a roller table for carrying a plate, means for driving the roller table, a powder hopper arranged above the roller table, transversely movable brushes for brushing the plate, means for causing powder to fall from said hopper when the plate
40 is first passing thereunder, means for turning the plate a part of a revolution after
45

passing under the hopper, means for reversing the travel of the roller table, means for operating said brushes after the reversing of the travel of the roller table, means for baking the powder to the plate after being brushed, and means for cooling the plate
50 after the baking of the powder thereto.

19. In a plate powdering machine, the combination of a roller table for carrying a plate, means for driving the roller table, a powder hopper arranged above the roller table, transversely movable brushes for brushing the plate, means for causing powder to fall from said hopper when the plate
55 is first passing thereunder, means for turning the plate a part of a revolution after passing under the hopper, means for reversing the travel of the roller table, means for operating said brushes after the reversing of the travel of the roller table, means for baking the powder to the plate after being
60 brushed, a platform for receiving the plate after the baking of the powder thereto, and an air blast for cooling the plate when upon said platform.

20. In a plate powdering machine, the combination of a roller table for carrying a plate, means for driving the roller table, a powder hopper arranged above the roller table, transversely movable brushes for brushing the plate, means for causing powder to fall from said hopper when the plate
65 is first passing thereunder, means for turning the plate a part of a revolution after passing under the hopper, means for reversing the travel of the roller table, means for operating said brushes after the reversing of the travel of the roller table, means for baking the powder to the plate after being
70 brushed, a traveling platform for receiving the plate after the baking of the powder thereto, and means for stopping the platform, means for cooling the plate when upon the platform, and means for reversing the travel of the platform.

21. In a plate powdering machine, the combination of a roller table for carrying a plate, means for driving the roller table, a powder hopper arranged above the roller table, transversely movable brushes for brushing the plate, means for causing powder to fall from said hopper when the plate
75 is first passing thereunder, means for turning the plate a part of a revolution after passing under the hopper, means for reversing the travel of the roller table, means for operating said brushes after the reversing of the travel of the roller table, means for baking the powder to the plate after being
80 brushed, a traveling platform for receiving the plate after the baking of the powder thereto, and means for stopping the platform, means for cooling the plate when upon the platform, and means for reversing the travel of the platform.

681

the platform, and means for bringing the machine to a standstill after the reversing of the travel of the roller table and said platform several times.

5 22. In a plate powdering machine, the combination of a roller table for carrying a plate, means for driving the roller table, a powder hopper arranged above the roller table, transversely movable brushes for 10 brushing the plate, clutch mechanism for reversing the travel of the roller table, and means for operating the clutch mechanism.

15 23. In a plate powdering machine, the combination of a roller table for carrying a plate, means for driving the roller table, a powder hopper arranged above the roller table, transversely movable brushes for brushing the plate, clutch mechanism for reversing the travel of the roller table, a 20 rotatable worm shaft, and a control carriage mounted on the worm shaft for operating the clutch mechanism.

25 24. In a plate powdering machine, the combination of a roller table for carrying a plate, means for driving the roller table, a powder hopper arranged above the roller table, clutch mechanism for reversing the travel of the roller table, a control carriage for operating the clutch mechanism, transversely moving brushes for brushing the plate after the reversing of the travel of the roller table, and means operated by the control carriage for baking the powder to the plate.

30 35. 25. In a plate powdering machine, the combination of a roller table for carrying a plate, means for driving the roller table, a powder hopper arranged above the roller table, clutch mechanism for reversing the travel of the roller table, a control carriage for operating the clutch mechanism, transversely moving brushes for brushing the plate after the reversing of the travel of the roller table, burners for baking the powder 40 to the plate, the burners being operated by the control carriage, and means for cooling the plate after the baking of the powder thereto.

50 26. In a plate powdering machine, the combination of a roller table for carrying a plate, means for driving the roller table, a powder hopper arranged above the roller table, clutch mechanism for reversing the travel of the roller table, a control carriage 55 for operating the clutch mechanism, transversely moving brushes for brushing the plate after the reversing of the travel of the roller table, burners for baking the powder to the plate, the burners being operated by 60 the control carriage, a traveling platform for receiving the plate after the baking of the powder thereto, means for stopping the platform with the plate thereon, means for cooling the plate when upon the platform, 65

and means for reversing the travel of said platform.

27. In a plate powdering machine, the combination of a roller table for carrying a plate, means for driving the roller table, a powder hopper arranged above the roller table, clutch mechanism for reversing the travel of the roller table, a control carriage for operating the clutch mechanism, transversely moving brushes for brushing the plate after the reversing of the travel of the roller table, burners for baking the powder to the plate, the burners being operated by the control carriage, a traveling platform for receiving the plate after the baking of the powder thereto, means for stopping the platform with the plate thereon, means for cooling the plate when upon the platform, stopping mechanism adapted to bring said roller table and said platform to a standstill after the travel thereof has been reversed several times, and the stopping mechanism being operated by said control carriage.

28. In a plate powdering machine, the combination of a roller table for carrying a plate, means for driving the roller table, a powder hopper arranged above the roller table, a rack for turning the plate a quarter of a revolution, clutch mechanism for reversing the travel of the roller table, a control carriage for operating the rack and the clutch mechanism, transversely moving brushes for brushing the plate after the reversing of the travel of the roller table, and means operated by the control carriage for baking the powder to the plate after being brushed.

29. In a plate powdering machine, the combination of a roller table for carrying a plate, means for driving the roller table, a powder hopper arranged above the roller table, a rack for turning the plate a quarter of a revolution, clutch mechanism for reversing the travel of the roller table, a control carriage for operating the rack and the clutch mechanism, transversely moving brushes for brushing the plate after the reversing of the travel of the roller table, and burners for baking the powder to the plate after being brushed, the burners being operated by the control carriage, a traveling platform for receiving the plate after the baking of the powder thereto, means for stopping the platform with the plate thereon, means for cooling the plate when upon the platform, stopping mechanism adapted to bring said roller table and said platform to a standstill after the travel thereof has been reversed four times, and the stopping mechanism being operated by said control carriage.

30. In a plate powdering machine, the combination of a roller table for carrying

a plate, means for driving the roller table including clutch reversing mechanism, a powder hopper arranged above the roller table, transversely movable brushes for brushing the plate, the brushes being actuated from the means for driving the roller table, burners for baking powder to the plate, a worm shaft, the worm shaft being rotated by the means for driving the roller table, a control carriage actuated by the worm shaft, said clutch reversing mechanism and said burners being operated by the control carriage.

31. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, burners for baking powder to the plate, a traveling platform for receiving the plate, the platform being actuated by the means for driving the roller table, means for cooling the plate when upon the platform, a worm shaft, the worm shaft being rotated by the means for driving the roller table, a control carriage actuated by the worm shaft, said clutch reversing mechanism and said burners being operated by the control carriage.

32. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a rack for turning the plate a part of a revolution, burners for baking powder to the plate, a traveling platform for receiving the plate, the platform being actuated by the means for driving the roller table, a control carriage actuated by the worm shaft, said rack, said clutch reversing mechanism and said burners being operated by the control carriage.

33. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a rack for turning the plate a part of a revolution, burners for baking powder to the plate, a traveling platform for receiving the plate, the platform being actuated by the

means for driving the roller table, means for cooling the plate when upon the platform, means for stopping the travel of the platform, a worm shaft, the worm shaft being rotated by the means for driving the roller table, a control carriage actuated by the worm shaft, said rack, said clutch reversing mechanism and said burners being operated by the control carriage.

34. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a rack for turning the plate a part of a revolution, burners for baking powder to the plate, a traveling platform for receiving the plate, the platform being actuated by the means for driving the roller table, means for cooling the plate when upon the platform, means for stopping the travel of the platform, means for bringing the machine to a standstill after the reversing of the travel of the roller table several times, a worm shaft, the worm shaft being rotated by the means for driving the roller table, a control carriage actuated by the worm shaft, said rack, said clutch reversing mechanism, said burners, and said means for bringing the machine to a standstill, being operated by the control carriage.

35. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a rack for turning the plate a part of a revolution, burners for baking powder to the plate, a traveling platform for receiving the plate, the platform being actuated by the means for driving the roller table, a control carriage mounted upon and actuated by the worm shaft, said clutch reversing mechanism being operated by the control carriage, locking levers for holding the clutch reversing mechanism in either driving position, and the locking levers being disengaged by the control carriage.

36. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a worm shaft, the worm shaft being rotated by the means for driving the roller table, a control carriage mounted upon and actuated by the worm shaft, said clutch reversing mechanism being operated by the control carriage.

carriage, locking levers for holding the clutch reversing mechanism in either driving position, the locking levers being disengaged by the control carriage, means for holding the clutch reversing mechanism in neutral position, and means for releasing said last means.

37. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a worm shaft, the worm shaft being rotated by the means for driving the roller table, a control carriage mounted upon and actuated by the worm shaft, said clutch reversing mechanism being operated by the control carriage, locking levers for holding the clutch reversing mechanism in either driving position, the locking levers being disengaged by the control carriage, said clutch reversing mechanism including a shift rod, a pawl for limiting the movement of the shift rod to hold the clutch reversing mechanism in neutral position, and releasing means for disengaging said pawl.

38. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a worm shaft, the worm shaft being rotated by the means for driving the roller table, a control carriage mounted upon and actuated by the worm shaft, said clutch reversing mechanism being operated by the control carriage, a turning rack, the turning rack being below the top of the roller table, and means operated by the control carriage for lifting the turning rack above the surface of the roller and rotating it a part of a revolution.

39. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a worm shaft, the worm shaft being rotated by the means for driving the roller table, a control carriage mounted upon and actuated by the worm shaft, said clutch reversing mechanism being operated by the control carriage, a turning rack being below the top of the roller table, a fulcrumed lever for lifting the turning rack, a belt for rotating the turning rack, a bell-crank, a wire connecting the belt to the bell-crank, a sleeve

loosely mounted upon said worm shaft adapted to be moved by the control carriage, a strap pivoted to the sleeve and to said fulcrumed lever, and a sliding joint member connecting said bell-crank to the strap to cause the lifting of the turning rack before the rotating thereof.

40. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a worm shaft, the worm shaft being rotated by the means for driving the roller table, a control carriage mounted upon and actuated by the worm shaft, said clutch reversing mechanism being operated by the control carriage, burners for baking powder to the plate, a valve for admitting gas to the burners, a push rod for opening the valve, the push rod having a lug, an arm pivoted to said control carriage for engaging the lug to move the push rod, a locking bar for holding the valve open, and a cam plate for throwing said arm out of engagement with the lug and for causing the arm to force the locking bar to release the push rod.

41. In a plate powdering machine, the combination of a roller table for carrying a plate, means for driving the roller table including clutch reversing mechanism, a powder hopper arranged above the roller table, transversely movable brushes for brushing the plate, the brushes being actuated from the means for driving the roller table, a worm shaft, the worm shaft being rotated by the means for driving the roller table, a control carriage mounted upon and actuated by the worm shaft, said clutch reversing mechanism being operated by the control carriage, locking levers for holding the clutch reversing mechanism in either driving position, the locking levers being disengaged by the control carriage, said clutch reversing mechanism including a shift rod, a pawl for limiting the movement of the shift rod to hold the clutch reversing mechanism in neutral position, a threaded shaft, the threaded shaft being rotated in one direction from the means for driving the roller table, a releasing carriage loosely mounted upon the threaded shaft, a toothed bar slidably mounted in the releasing carriage, a guide bar, the guide bar being pivoted to links, the toothed bar having a recess for receiving the guide bar, an arm projecting from the releasing carriage for forcing said pawl upwardly, a spring for throwing the guide bar upwardly and for pulling the releasing carriage back to its original position, the guide bar being forced to its down position by said control carriage, a pawl for re-

- taining the guide bar in its down position, and a finger extending from the releasing carriage for disengaging said pawl.
42. In a plate powdering machine, the combination of a roller table for carrying a plate, means for driving the roller table including clutch reversing mechanism, a powder hopper arranged above the roller table, a corrugated roller at the outlet of the powder hopper, the corrugated roller being driven from the roller table when it travels in one direction, a round brush in contact with the corrugated roller, the round brush being rotated from the corrugated roller, a transversely movable brush, actuated from the roller table, the last brush being held in down position when the roller table is traveling in one direction and forced upwardly when traveling in the other direction, transversely movable brushes for brushing the plate, and the last mentioned brushes being actuated from the means for driving the roller table when the roller table is traveling in one direction.
43. In a plate powdering machine, the combination of a roller table for carrying a plate, means for driving the roller table including clutch reversing mechanism, a powder hopper arranged above the roller table, a worm shaft, the worm shaft being rotated by the means for driving the roller table, a control carriage mounted upon and actuated by the worm shaft, said clutch reversing mechanism being operated by the control carriage, the means for driving the roller table including a motor, a switch for operating the motor, a slidably mounted bar, a spring for forcing the bar in one direction to close the switch, a spring tending to open the switch, a pivoted pawl for holding the switch in open position, said bar having two sets of ratchet teeth, a dog adapted to engage the teeth of one set, a push pawl adapted to engage the teeth of the other set, the push pawl being pivoted to a pivotally supported lever, the lever being actuated by said control carriage each time it returns to its original position for forcing said bar a distance of one tooth, and a roller carried by said bar for actuating said pivoted pawl to release the switch lever when the bar has moved the distance of each set of teeth.
44. In a plate powdering machine, the combination of a roller table for carrying a plate, means for driving the roller table including clutch reversing mechanism, a powder hopper arranged above the roller table, a sprocket wheel at each side of the roller table, a sprocket chain passing around the sprocket wheels, brushes carried by the sprocket chain for brushing the plate, guide rails, roller wheels for supporting the brushes upon the rails, and one of the said sprocket wheels being driven from the means for driving the roller table when the roller table is traveling in one direction.

plate, means for driving the roller table including clutch reversing mechanism, a powder hopper arranged above the roller table, a corrugated roller at the outlet of the powder hopper, the corrugated roller being driven from the roller table when it travels in one direction, a round brush in contact with the corrugated roller, the round brush being rotated from the corrugated roller, a vertically movable brush, actuated from the roller table, the last brush being held in down position when the roller table is traveling in one direction and forced upwardly when traveling in the other direction, transversely movable brushes for brushing the plate, and the last mentioned brushes being actuated from the means for driving the roller table when the roller table is traveling in one direction.

45. In a plate powdering machine, the combination of a roller table for carrying a plate, means for driving the roller table including clutch reversing mechanism, a powder hopper arranged above the roller table, a sprocket wheel at each side of the roller table, a sprocket chain passing around the sprocket wheels, brushes carried by the sprocket chain for brushing the plate, guide rails, roller wheels for supporting the brushes upon the rails, and one of the said sprocket wheels being driven from the means for driving the roller table when the roller table is traveling in one direction.

In testimony whereof I affix my signature.

WILLIAM J. LOGAN.
